CLAIM

The ornamental design for a power supply, as shown and described.

DESCRIPTION

FIG. 1 is a front perspective view of a power supply; FIG. 2 is a front elevational view of the power supply of FIG. 1;

FIG. 3 is a rear elevational view of the power supply of FIG. 1;

FIG. 4 is a left side elevational view of the power supply of FIG. 1;

FIG. 5 is a right side elevational view of the power supply of FIG. 1;

FIG. 6 is a top plan view of the power supply of FIG. 1; and, FIG. 7 is a bottom plan view of the power supply of FIG. 1. The broken lines having consistent dash lengths (dash-dash-dash) show unclaimed portions of the power supply in FIGS. 1-7 and form no part of the claimed design.

1 Claim, 6 Drawing Sheets
